UNITED STATES PATENT OFFICE

172,877

TOY AUTOMOBILE

Elliot Handler, Los Angeles, and Joseph Kossoff,
Hawthorne, Calif.

Application January 25, 1954, Serial No. 28,640

Term of patent 7 years

(Cl. D34—15)

To all whom it may concern:

Be it known that we, Elliot Handler and Joseph Kossoff, both citizens of the United States and residing, respectively, in Los Angeles, county of Los Angeles, State of California, and Hawthorne, county of Los Angeles, State of California, have invented a new, original, and ornamental Design for a Toy Automobile, of which the following is a specification, reference being had to the accompanying drawings forming part thereof.

Figure 1 is a front perspective view of a toy automobile, embodying our new design.

Figure 2 is a rear perspective view thereof.

Figure 3 is a top view thereof.

Figure 4 is a side view thereof.

Figure 5 is a front view thereof.

Figure 6 is a rear view thereof.

We claim:

The ornamental design for a toy automobile, substantially as shown.
